(57) **CLAIM**

The ornamental design for a bucket squeegee as shown and described.

DESCRIPTION

FIG. 1 is a top front elevation view of a bucket squeegee showing my new design;

FIG. 2 is a top plan view of the bucket squeegee of FIG. 1; FIG. 3 is a bottom plan view of the bucket squeegee of FIG. 1;

FIG. 4 is a side plan view of the bucket squeegee of FIG. 1; FIG. 5 is an opposite side plan view of the bucket squeegee of FIG. 1; and,

FIG. 6 is a front plan view thereof of the bucket squeegee of FIG. 1.

The broken lines are included for the purpose of illustrating non-claimed subject matter and form no part of the claimed design.

1 Claim, 6 Drawing Sheets
